UNITED STATES PATENT OFFICE.

EDWIN SANFORD PHELPS, OF ELIZABETH, NEW JERSEY.

ALARM FOR AUTOMOBILE AND OTHER WHEEL-TIRES.

1,138,407.

Specification of Letters Patent.

Patented May 4, 1915.

Application filed April 19, 1906. Serial No. 312,693.

To all whom it may concern:

Be it known that I, EDWIN S. PHELPS, a citizen of the United States, residing in Elizabeth, in the county of Union and State 5 of New Jersey, have invented certain new and useful Improvements in Alarms for Automobile and other Wheel-Tires; and I do declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

The purpose of the invention is to provide an alarm signal to warn an automobilist when a tire of the vehicle becomes deflated, so that being warned the vehicle may be 20 checked in speed, or stopped so as to avoid danger or an accident.

It comprises a member adapted to be attached to the spoke of the wheel and carrying a detonating cap or blank cartridge, a 25 hammer and a trigger, the trigger being located adjacent to the felly or tire so that upon deflation of the tire pressure of the tire against the trigger, or contact of the trigger with the ground, will cause the trigger 30 to act upon the hammer so that through the hammer the cap or cartridge will be exploded and give the alarm.

To the accomplishment of the foregoing and such other objects as may hereinafter 35 appear the invention will now be described and then sought to be specifically defined by the claims, reference being had to the accompanying drawings illustrating the invention and in which—

40 Figure 1 is an elevation partly in section showing the alarm applied to the spoke of a wheel; Fig. 2 is a perspective of the hammer or firing pin; Fig. 3 a modication of the lower end of the trigger-rod; and Fig. 45 4 a perspective of a tool for screwing and unscrewing the cartridge holder.

In the drawing the numeral 1 designates a tube provided with an apertured cap or cartridge seat 2 screwed or otherwise sealed 50 therein and with a cartridge or detonating cap holder 3 which is likewise screwed therein and provided with a cavity 4 to receive the shell portion of the cartridge.

The numeral 5 designates a hammer or 55 firing pin fitting within the tube and so formed as to be held normally in a retracted

position therein. The preferred construction is to form the shank of the pin with the head 6 to engage a suitable spring-catch 7 by which the pin will be held in its retracted position. This spring-catch may be a corrugated or notched flat spring secured at one end to the inside of the tube or barrel, and the head of the firing pin may be formed with the recess 8 to receive the spring-catch 60 and with a tooth or shoulder 9 with which the spring will engage and hold the firing pin until released.

The numeral 10 indicates a coiled spring against which the head of the firing pin 70 presses when the pin or hammer is in its retracted or cocked position. Within the tube or barrel is a trigger which in one form may consist of a sliding member or plunger-rod 11 formed with a shoulder or head 12 to bear 75 against one end of the coiled spring 10, a part of said rod extending within the coiled spring and a part extending beyond the end of the tube or barrel, the inner end of said trigger-rod normally being out of contact 80 with the head of the hammer and the outer end of the rod being formed with a knob 13 which will lie against or be in proximity to the tire or felly of the wheel. This trigger-rod plays through a corresponding opening 85 in a cap 14 which screws into the end of the tubular barrel and prevents the entire withdrawal of the trigger-rod except when desired to be taken out. The coiled spring affords a yielding cushion for the trigger- 90 rod and permits a limited movement thereof without its end coming in contact with the hammer or pin. When the hammer is cocked the coiled spring is under tension. If the tire becomes deflated from any cause it 95 presses against the knob end of the trigger, or said end comes in contact with the ground, and the trigger is pressed inward so as to bring its end against the hammer and force it from locking engagement with its holding spring, when the expansion of the coiled spring projects the hammer or firing pin against the primed head of the cap or cartridge and causes the same to explode and give the alarm. It is preferred to render the 100 knob adjustable by threading it on the end of the trigger-rod so that it may conform to different shapes or designs of tires.

If desired the projecting portion of the trigger-rod may be made somewhat flexible 110 by forming it of a strong and closely coiled spring 15 which will be connected at one

end to the outer portion of the trigger-rod and at the other end having the knob 13 connected thereto by a stud 16 as shown in Fig. 3 of the drawing. The tube or barrel 5 will be formed with clips 17 and clamping nuts 18 by which it may be locked to the wheel spoke; and in practice it is preferred to provide each wheel with one of the devices, and by preference the tubes or barrels 10 will be made to lie on the inside of the spokes so as not to be tampered with by mischievously disposed or officious persons.

When a cap or cartridge is to be applied or removed, the cap or cartridge holder is 15 unscrewed and the spent cartridge removed and a fresh one substituted. Before the holder is put in place, the hammer or pin is pressed down or cocked, and for that purpose a tool 19 formed with a concave end 20 conforming to the end of the firing pin may be used. This tool is also formed with pins 21 on one face to engage corresponding holes 20 formed in the cartridge holder and also in the closing cap at the opposite end of the 25 barrel so as to screw and unscrew them into and out of place.

I have described and illustrated the preferred construction, but the parts can be varied within wide range without departing 30 from the essentials of the invention as set forth in the claims.

Having described my invention and set forth its merits, what I claim is:—

1. A detonating alarm for automobile or 35 other wheel tires, comprising a cap or cartridge holder, a slideable hammer or firing pin and a trigger, and means for securing the alarm to a wheel with one end of the trigger in proximity to the tire so as to be projected on deflation of the tire to cause the hammer to explode the cartridge, said trigger having a normally limited longitudinal movement without rendering the hammer active to explode the cartridge, substantially as described.

2. A detonating alarm for automobile or 50 other wheel tires, comprising a cap or cartridge holder, a hammer or firing pin and means for holding the same in retracted position, a yielding trigger for releasing the hammer, said trigger having a normal limited reciprocatory movement without releasing the hammer, and means for attaching the alarm to a wheel, said trigger having a 55 part thereof in proximity to the tire of a wheel and adapted to be actuated on deflation of the tire to release the hammer, substantially as described.

3. A detonating alarm for automobile or 60 other wheel tires, comprising a cap or cartridge holder, a hammer or firing pin and means for holding the same in retracted position, a yielding trigger for releasing the hammer, said trigger having a normal limited reciprocatory movement without releasing the firing pin, means for attaching the alarm to a wheel, and a head adjustable 65 on the trigger adjacent to a tire of a wheel, substantially as described.

4. A detonating alarm for automobile or 70 other wheel tires, comprising a cap or cartridge holder, a hammer or firing pin, means for holding the same in a retracted position, a spring for impelling the hammer or firing pin when released, a cushioned trigger in co-operative relation to the hammer and having a part adjacent to a tire to be actuated on deflation of the tire, said trigger having a limited reciprocatory movement without releasing the hammer or firing pin, and means 75 for attaching the alarm to a wheel, substantially as described.

5. A detonating alarm for automobile or 80 other wheel tires, comprising a tubular barrel, a cap or cartridge holder, fitting in one end of the barrel, a seat for the cap or cartridge in the barrel back of the holder, a hammer or firing pin operable through said seat, means for holding the hammer in retracted position, a trigger for releasing the 85 hammer, and means for attaching the alarm to a wheel in position for the trigger to be actuated on deflation of a wheel tire, substantially as described.

6. A detonating alarm for automobile or 90 other wheel tires, comprising a tubular barrel, a cap or cartridge holder fitting in said barrel, a hammer or firing pin, means for holding the same in a retracted position, a spring for impelling said hammer or firing 95 pin, and a trigger for projecting the hammer or firing pin, said trigger consisting of a slideable rod having a shoulder within the barrel to bear against said spring, a portion of said rod passing through the spring to 100 release the hammer or firing pin, and a portion thereof extending outside of the barrel, substantially as described.

In testimony whereof I affix my signature in presence of two witnesses.

EDWIN SANFORD PHELPS.
